UNITED STATES PATENT OFFICE.

CARL J. SUNDELL, OF CHICAGO, ILLINOIS.

COMBINED TOY AND SUPPORT.

1,318,024.

Specification of Letters Patent.

Patented Oct. 7, 1919.

Application filed June 14, 1919. Serial No. 304,167.

To all whom it may concern:

Be it known that I, CARL J. SUNDELL, a citizen of the United States, residing at Chicago, in the county of Cook and State of Illinois, have invented certain new and useful Improvements in Combined Toys and Supports, of which the following is a specification.

This invention relates to improvements in 10 a combined toy and support therefor to be used in connection with a child's chair, buggy or carriage, for the amusement of the child and for the retention of its toys or playthings, in such a way as to prevent them 15 from getting out of reach or falling from the chair or vehicle occupied by the child, and it consists in certain peculiarities of the construction, novel arrangement and operation of the various parts thereof as will be 20 hereinafter more fully set forth and specifically claimed.

The principal object of the invention is to 25 provide a device of the above mentioned general character which shall be simple and inexpensive in construction, strong and durable, with its parts so made and arranged that it can be readily attached to the upright posts of the back of a child's chair and placed in its operative position to serve as a 30 support for a toy or toys, as well as to assist in guarding or preventing the child falling forwardly from the chair, or if desired, can be easily turned to an inoperative position at 35 the back of the chair, or detached therefrom.

Another object is to provide simple and efficient means for maintaining the support at a proper elevation to permit the toys thereon to be manipulated by the child or 40 for its amusement and against accidental lowering of the support. Other objects and advantages of the invention will be disclosed in the subjoined description and explanation.

45 In the accompanying drawing which serves to illustrate the invention,

Figure 1 is a view in side elevation of the upper portion of a child's chair showing by continuous lines the support and toy in its 50 operative position, and by dotted lines in its inoperative position.

Fig. 2 is a greatly enlarged view partly in section and partly in elevation of the device, taken on line 2—2 of Fig. 1, looking in the direction indicated by the arrows, and 55

Fig. 3 is a fragmental view partly in section taken on line 3—3 of Fig. 2, looking in the direction indicated by the arrows.

Corresponding numerals of reference refer to like parts throughout the different views 60 of the drawing.

The numeral 5 designates the arms of the device, which may be made of any suitable size, form and material, but which are located in parallelism with one another, and 65 each of said arms has near each of its ends a transverse opening therein.

Located in the openings in the front portions of the arms or bars 5, is a rod 6 which has each of its ends screw-threaded. This 70 rod or bar 6 is of a suitable length to extend across the body and arms of a child's chair, which is designated as a whole by the reference numeral 7, and a portion of which is illustrated in Fig. 1 of the drawing. As 75 before stated, each end of the rod 6 is screw-threaded, which portions are extended through suitable openings in the arms or bars 5 near their front ends and said arms or bars are secured in place on the rod 6 by 80 means of nuts 8 and 9, which are threaded on said rod and clamp the bars or arms 5 therebetween, as will be readily understood by reference to Fig. 2 of the drawing.

Mounted on the rod 6 is a substantially 85 U-shaped bail or supporting member 10, the arms 11 of which are provided at their free ends with loops or eyes 12 for the loose reception of the rod 6 on which rod said loops or eyes are mounted inwardly of the 90 nuts 8 as can be clearly seen in Fig. 2 of the drawing.

The bail 10 being loosely mounted at the ends of its arms 11 on the rod 6 will be capable of being easily turned on said rod 95 so as to lie on either surface of the arms or bars 5 when the device is in its inoperative position.

In order to maintain the arms 11 of the bail 10 in a vertical position so as to support 100 the rod 6 and the bars 5 of the device at a suitable elevation above the table or tray

13 of the chair 7, which table or tray may be of the ordinary or any preferred construction, and is mounted on the upper portions of the front parts of the arms 14 of the 5 chair in the usual manner, I provide each of the bars or arms 5 near its front end with a downwardly and forwardly extended bracket 15, each of which has its lower portion provided with prongs 16 and 17, which extend 10 laterally and inwardly as shown in Fig. 2 and are for the purpose of engaging between said prongs the arms 11 of the bail 10 so as to hold said bail and arms in a vertical position, it being understood that the horizontal part of the bail 10 will rest on the 15 upper surface of the tray 13 or table of the chair. As the loops or eyes 12 of the bail 10 are loosely mounted on the rod 6, and as the arms 11 of said bail are somewhat flexible, it is apparent that said arms may 20 be disengaged from the prongs 16 and 17 of the brackets 15 by simply pressing them toward each other. When thus released from the prongs of the brackets 15, it is apparent that the supporting bail 10 can be 25 turned on the rod 6 so as to rest on the upper or lower surfaces of the arms of bars 5, which have their rear ends pivotally secured by means of thumb screws 18, or otherwise, 30 to the uprights 19 of the back of the chair or other support in connection with which the device may be used.

Mounted on the rod 6 for rotation, is a cylindrical cage which consists of a pair of 35 circular end pieces 20, which are held in spaced relation to one another by means of a series of transversely disposed brace rods 21, located at or near the peripheries of said end pieces. This cage may be prevented by 40 longitudinal movement on the rod 6 by means of collars 22 secured to said rod at the outer surfaces of the heads or end pieces 20 of the cage.

Mounted on the rod 6 within the cage is 45 one or more flexible wires or members 23, which as shown in Fig. 2 are spirally and loosely wound on said rod about midway between their ends, as at 24. On the lower end of each of the wires or members 23 is 50 loosely mounted a spherical member 25 such as a glass marble or the like, which as indicated will be suspended at a distance above the path of the travel of the brace rods 21 of the cage.

55 The upwardly extended portions of the wires or members 23 project sufficient at their free ends beyond the peripheries of the end pieces 20 of the cage to intermittently engage the brace rods 21 to the end that 60 when the cage is revolved on the rod 6, the pendants 25 will be given an oscillating movement which will be amusing and attractive to the child or operator.

It will be noticed that each of the mem-

bers 23 is provided between the shaft 6 and 65 the ends of said members which contact with the brace rods 21 with a spiral coil which is for the purpose of giving more resiliency to the members 23 and thereby causing the pendants to vibrate more frequently and for 70 a longer period.

Rotatably mounted on the rod 6 near one end 20 of the cage, is a cylindrical drum 26, which may be made of tin or other suitable material, and has its cylindrical wall provided with corrugations 27 which are employed for the purpose of causing balls or marbles 28 located in said drum to rattle or produce a noise when the drum is rotated, for the amusement of the child.

80 While I have shown the invention as being applied to a child's chair, yet it is apparent that the rear ends or portions of the arms or bars 5 may be secured to the upright portions of the back of a baby carriage or buggy, 85 and that the supporting bail 10 may rest on a suitable support or the front portion of the carriage or buggy in front of the child or occupant in which the construction, arrangement and operation of the parts will be the 90 same as above described.

It will be obvious that my invention not only provides a plaything and support therefor, but also furnishes a guard or protector to assist in preventing the child falling forwardly or laterally from the chair or other device which he occupies, as the arms 5 and the rod 6 together with the back of the chair will provide a safe inclosure.

Having thus fully described my invention 100 what I claim as new and desire to secure by Letters Patent is,

1. In a device of the character described, the combination with a pair of parallel arms pivotally supported at one of their ends, of 105 a rod connecting them transversely at their other ends, a substantially U-shaped supporting member loosely mounted at its ends on said rod inwardly of said arms, and a member rotatably mounted on the rod between the ends of said supporting member.

2. In a device of the character described, the combination with a pair of parallel arms pivotally supported at one of their ends, of 115 a rod connecting them transversely at their other ends, a substantially U-shaped supporting member loosely mounted at its ends on said rod inwardly of said arms, a bracket secured to each of said arms near its free end and extended downwardly therefrom and having on its lower portion a pair of inwardly extended and spaced apart prongs to engage the side portions of said supporting member, and a member rotatably mounted on the rod between the ends of said supporting member.

3. In a device of the character described, the combination with a pair of parallel arms

pivotedly supported at one of their ends to a fixed support, of a rod connecting them transversely at their other ends, a cylindrical cage rotatably mounted on said rod and having spaced apart bracing members uniting its ends, at least one flexible member loosely mounted on said rod within said cage, and having one of its ends extended into the path of said bracing members and provided between the said end and said rod with a resilient coil, and a weighted pendant on the other end of said flexible member. 10

CARL J. SUNDELL.
